UNITED STATES PATENT OFFICE.

EDWARD TONEY, OF NILES, MICHIGAN, ASSIGNOR TO THE KAWNEER COMPANY, OF NILES, MICHIGAN, A CORPORATION OF MICHIGAN.

DESIGN FOR A MOLDING.

Application filed March 23, 1928. Serial No. 25,975. Term of patent 14 years.

To all whom it may concern:

Be it known that I, EDWARD TONEY, a citizen of the United States, residing at Niles, in the county of Berrien and State of Michigan, have invented a new, original, and ornamental Design for Molding, of which the following is a specification, reference being had to the accompanying drawing forming a part

thereof, wherein the figure is a view in perspective of my new and original design for molding.

I claim:

The ornamental design for a molding substantially as shown.

EDWARD TONEY.
